UNITED STATES PATENT OFFICE.

REN S. CLARK, OF CHICAGO, ILLINOIS, ASSIGNOR TO HUNTER CLARK VENTILATING SYSTEM COMPANY, OF CHICAGO, ILLINOIS, A CORPORATION OF ILLINOIS.

VENTILATOR.

Application filed August 22, 1921. Serial No. 494,204.

To all whom it may concern:

Be it known that I, REN S. CLARK, a citizen of the United States, and a resident of Chicago, in the county of Cook and State 5 of Illinois, have invented a new and useful Ventilator, of which the following is a specification.

This invention relates to ventilators and relates particularly to ventilators especially 10 designed and particularly adapted for ventilating theatres and other auditoriums and which comprise base portions consisting of thimbles secured in holes in the floor, usually beneath the seats, and are connected by 15 pipes or flues with a fan or other source of supply of air, and said ventilators also comprising a cap having depending flanges at their edges and which are adjustably mounted on the base portions of said ventilators 20 so as to be adjustable towards and from the same, in order to vary the size of the free spaces or openings between the depending edges of said flanges and the thimbles.

The object of the invention is to provide 25 improved means for supporting the cap upon the base portion of the ventilator, which will afford a rigid support for said cap under all conditions of use and which are so positioned that they will leave practically unobstructed 30 discharge space or opening between the base and cap of the ventilator.

To effect the foregoing object, the cap supporting means of my improved ventilator consist of a spider, preferably formed integral with the base portion of the ventilator 35 and spaced cams formed within the cap of the ventilator, between the center and the circumference thereof. To afford a stable support for said cap, there are at least three 40 of said cams, said cams being similar and being arranged at angles of substantially 120° from each other with reference to the center of the ventilator. Said cams are provided with similar inclined surfaces which 45 extend at angles to the surface of the cap on which they are formed and are adapted to rest on corresponding symmetrically arranged lugs or projections formed in proper positions on the arms of the supporting spider, said cap being held in adjusted positions, corresponding to an air 50 discharge opening of desired size, by means of serrations or notches formed on said cam surfaces with which the lugs or projections 55 on said spider are adapted to interlock, the

edges of said lugs or projections upon which said cam surfaces rest being fitted to the serrations or notches therein.

My invention also comprises the various other features and details of construction 60 hereinafter described and claimed.

In the accompanying drawing, in which my invention is fully illustrated,

Figure 1 is a top plan view of a ventilator embodying my invention, shown as attached to a floor.

Figure 2 is a bottom plan view of said ventilator.

Figure 3 is an enlarged sectional view of the ventilator taken on the line 3—3 of Fig. 1.

Figure 4 is an enlarged fragmentary top plan view of the central portion of the spider forming part of the base portion of the ventilator, showing the lugs on which the cap of the ventilator rests directly, and

Figure 5 is a fragmentary sectional detail view on the line 5—5 of Fig. 4.

Referring now to the drawings, A designates, as a whole, the base portion of my improved ventilator, and B the cap thereof, both of which, as regards their usual features, may be of any usual or desired construction and which will readily be understood by persons familiar with the art from 85 an examination of the drawings and without a description thereof in detail.

Briefly, the base portion A comprises a thimble 1 adapted to be inserted into a hole in the floor in communication with a ventilating flue or pipe, and a flange 2 which projects outwardly and rests upon the floor and is adapted to be screwed or otherwise rigidly secured thereto. Also, the cap comprises a plate 3, having a depending flange 4 at its outer edge.

As shown, said base A and cap B are circular, but the shape thereof may be variously changed without departing from my invention.

In accordance with my invention, the cap or hood B is supported upon the base A in the following manner:—Formed on the base A is a spider *a* comprising a hub 5 which is connected with the thimble 1 of the base by arms 6, said hub 5 being positioned above the plane of the top of the base A and the spider arms 6 being corresponding inclined.

The cap B is detachably connected to the base A by a screw 7 inserted through a hole 110

formed centrally in said cap, the lower end of which has screw-threaded engagement with a hole formed in the hub 5 of the spider *a*, a nut 8 being preferably cast into 5 said hub in proper position for engagement by said screw 7. Said cap B is adjustably supported in spaced relation to the base A by means of lugs or projections 9 formed on the spider arms 6 and cams 10 on the 10 cap B, said cams being provided with inclined or cam surfaces 11 adapted to rest in contact with the lugs or projections 9 on the spider arms 6, said cam surfaces being notched or serrated, as shown at 12, and 15 the ends of the lugs or projections 9 which contact with said cam surfaces being shaped to fit the notches or serrations therein.

The cams 10 are confined on the projections 9 by shoulders 13 on said lugs or projections, which embrace the outer sides of 20 said cams.

To effect the object of the invention as it relates to providing a rigid support for the cap B, the supporting cams 10 and lugs or 25 projections 9 are positioned at a distance from the center of the ventilator—that is from the screw 7 which connects said cap to the base of the ventilator—and comprise at least three sets of supporting cams and 30 lugs, or projections arranged concentrically around the screw 7 at substantially equal distances from one another.

Also, to effect the object of the invention, as it relates to providing a substantially 35 unobstructed air discharge space between the lower edge of the cap flange 4 and the top of the base portion A, the cams 10 are arranged wholly within the cap B and at a distance inside of the depending flange 4 of 40 said cap, the spider arms 6 being preferably inclined to the plane of the base portion A of the ventilator, whereby it is rendered

possible to use relatively short lugs or projections 9 and a relatively short screw 7; and also raising the hub 5 and the adjacent 45 portions of the spider arms 6 well into the cap B, where they will obstruct the air discharge passageway only very little.

I claim:

1. In a ventilator of the type described, 50 the combination of a base portion, a cap, and means for adjustably mounting said cap on said base, comprising a spider on said base, a screw which extends through a hole in said cap and has threaded engagement with the hub of said spider, cams formed within said cap, said cams being provided with serrated surfaces adapted to engage seats formed on said spider arms, substantially as described. 55

2. A ventilator as specified in claim 1, in which the cap supporting seats on the spider arms are formed at the ends of lugs thereon, substantially as described.

3. A ventilator as specified in claim 1, in 60 which the cap supporting cams are arranged intermediate the screw which connects the cap to the base and the marginal flange of said cap and at an appreciable distance from both said screw and flange, substantially as described. 65

4. A ventilator as specified in claim 1, in which the spider arms are inwardly and upwardly inclined, substantially as described. 70 75

5. A ventilator as specified in claim 1, in which the cap supporting seats on the spider arms are shaped to fit the serrations in the cams on the cap, substantially as described.

In testimony that I claim the foregoing 80 as my invention, I have hereunto affixed my signature this 15th day of August, 1921.

REN S. CLARK.
